UNITED STATES PATENT OFFICE.

HERBERT E. KEELER, OF NEW YORK, N. Y.

CURTAIN-FIXTURE.

SPECIFICATION forming part of Letters Patent No. 727,378, dated May 5, 1903.

Application filed June 5, 1902. Serial No. 110,247. (No model.)

To all whom it may concern:

Be it known that I, HERBERT E. KEELER, citizen of the United States, and a resident of New York, in the county and State of New York, have invented certain new and useful Improvements in Curtain-Fixtures, of which the following is a specification, taken in connection with the accompanying drawings, which form a part of the same.

10 This invention relates to curtain-fixtures which are especially adapted for use in connection with spring-actuated curtains and are self-aligning to maintain such curtains in parallel position as they are raised and lowered.

15 In the accompanying drawings, in which the same reference characters refer to similar parts in the several figures, Figure 1 is an elevation partly in section, showing this curtain-fixture applied to a spring-actuated curtain. Figs. 2, 3, and 4 are detail views of one form of shoe. Figs. 5 and 6 are similar views of another modification. Figs. 7 and 8 show a modified construction. Figs. 9 and 25 10 show another form.

20 The curtain B is secured at its upper end to the spring-roller B', mounted, as usual, at the top of the window. The lower end of the curtain is formed to support the curtain-tube B³, which extends across the lower end of the curtain, as indicated in Fig. 1. The shoes D are mounted to reciprocate in the curtain-tube and are pressed outward, preferably yieldingly or under spring-pressure, into engagement with the guideways A in the posts A'. These shoes are provided with face guiding members or rolls D², mounted in the shoes and preferably suitably separated, so that the outward pressure tends to keep these shoes

40 parallel to the guideways, and in this manner the curtain-tube and the lower end of the curtain are maintained in parallel position, so that the curtain-fixture is self-aligning. These face guiding members are preferably located 45 in the ends of the shoes to give the greatest self-aligning action. The shoes are also provided with lateral guiding members, which are pressed outward transversely into engagement with the sides A² of the guideways, 50 so that by this means the shoes grip the guideways and hold the curtain securely in any desired position. At the same time the

entire outward pressure exerted upon the shoes is effective in maintaining the alignment of the curtain-fixture, and the lateral 55 guiding members, since they are operated transversely, do not materially interfere with the self-aligning action of the face guiding members.

As is seen in Figs. 1, 2, 3, and 4, the curtain-tube B³ is provided with the collar B⁵, through which the rod C² passes, the inner end of each of these rods being connected with the handle C. These two handles project out through a suitable opening in the escutcheon C', this construction being similar to that disclosed in the patent to Keeler and Duncan, No. 689,195, dated December 17, 1901. The spindle B' is mounted in the outer end of the tube and is accurately guided thereby, so 70 that the shoe is accurately guided in its outward movement. The spindle and shoe at either end of the curtain-tube are pressed outward by the spiral spring B⁴, operating between the collar and the end of the spindle. 75 The shoe D is rigidly secured to the spindle and comprises the face guiding members or rolls D², pivoted at the ends of the shoe, as indicated, to engage the face A of the guideway. The shoe is also provided with the lateral guiding members E E', which, as indicated, are situated on either side of the shoe near the center of the same. E' consists of the pivoted grip, (shown in Fig. 4,) which moves about the pivot E² in the shoe and which is pivotally connected 80 to the rod C² by the pivot E³. The leaf-spring E⁴ engages this guiding member and presses it transversely into contact with the side A² of the guideway, thereby forcing the opposite lateral guiding member E into contact 85 with the guideway as well.

It will be seen that when the handles are pressed together each one of the movable grips E' is swung about its pivot E², so as to withdraw it transversely from contact with 95 the guideway. Thereafter when the grip has reached the limit of its pivotal movement the rod withdraws the shoe and spindle inward against the action of the spring B⁴, so that the face guiding members are withdrawn 100 from engagement with the guideway, the springs E⁴ and B⁴ being so proportioned that these operations take place as indicated.

It is not necessary in all cases that the

guiding members or the shoes shall be withdrawn from engagement with the guideways, as has been indicated. The shoes may, if desired, be mounted as shown in Fig. 6, in which the shoe indicated is rigidly secured to the spindle D', having at its upper end the plunger D⁵, fitting accurately within the curtain-tube B³. This plunger is formed sufficiently long to give a good bearing for the spindle as it is reciprocated. The spring D⁶ operates against the plunger to normally hold the face guiding members D² in the shoe in contact with the guideway. The ferrule B⁶, secured to the outer end of the tube, keeps the plunger in the tube. This shoe, as is indicated, is formed with the lateral guiding member E near the center of one side of the shoe, and on the opposite side of the shoe a leaf-spring F is secured, the central portion of this spring, which is adapted to engage the side A² of the guideway, constituting a movable grip or lateral guiding member. The spring operates to force the lateral guiding members transversely into engagement with the side of the guideway, so as to give the proper engagement with the sides of the guideway so as to maintain the curtain in any desired position.

The form of shoe indicated in Figs. 7 and 8 is provided with the face guiding members D², and this shoe engages the side A² of the guideway throughout substantially its entire extent, the side of the shoe being formed flat, as indicated, for this purpose, so as to constitute a lateral guiding member. The movable grip, which engages the opposite side of the guideway and operates transversely under the action of the spring F³, is given the form of a roll F', mounted in suitable bearings F², secured to the spring. This roll or lateral guiding member projects through a suitable opening in the shoe and engages the side of the guideway.

The shoe indicated in Figs. 9 and 10 comprises the face guiding members D³, which in this instance are mounted to engage the outside of the guideway A³, so as to have a self-aligning action. The lateral guiding members F⁴ are formed in this instance near their end of the shoe and are pressed transversely into engagement with the sides A² of the guideway by the leaf-spring F, secured to the side of the shoe. The central portion of this leaf-spring engages the side of the guideway and constitutes a movable grip or lateral guiding member, which, together with the other lateral guiding members, is spring-pressed transversely into engagement with the sides of the guideway.

It is of course understood that many modifications may be made by those familiar with this art without departing from the spirit of this invention. The exact shape and position of the various guiding members is not material, and the guiding members may be made of any desired form or material in order to give the proper action when they en-

gage the guideway. It is of course understood that the face guiding members do not need to be formed as rolls in every instance so long as they properly engage the guideway. Parts of this invention may be employed without using all of the same and, furthermore, may be used in connection with other devices well known in this art. I do not, therefore, wish to be limited to the disclosure which I have made in this case; but

What I claim as new, and what I desire to secure by Letters Patent, is set forth in the appended claims:

1. In a self-aligning curtain-fixture, a spring-actuated curtain, a curtain-tube mounted in the lower end of said curtain, shoes mounted to reciprocate in either end of said tube, each of said shoes being provided with face guiding members to engage guideways and with lateral guiding members which comprise pivoted grips, spring-pressed transversely into engagement with the guideway, rods connected to said grips and having handles projecting from said tube and springs to press said shoes outward into engagement with said guideways.

2. In a self-aligning curtain-fixture, a spring-actuated curtain, shoes mounted to reciprocate in said curtain, said shoes being provided with face guiding members to engage guideways and with lateral guiding members comprising movable grips, means to press said shoes outward to force said face guiding members into contact with said guideways, means to force said movable grips transversely into lateral engagement with said guideways and means to manually retract said movable grips.

3. In a self-aligning curtain-fixture, a spring-actuated curtain, shoes to coöperate with guideways, means to secure said shoes to said curtain to reciprocate with respect thereto, said shoes being provided with separated face guiding members and with lateral guiding members, springs to force said shoes outward to cause the engagement of said face guiding members with said guideways and means to force said lateral guiding members transversely into engagement with said guideways.

4. In a self-aligning curtain-fixture, a spring-actuated curtain, shoes to coöperate with guideways, means secured to said curtain in which said shoes are mounted to reciprocate with respect to said curtain, face guiding members in the ends of said shoes, spring-pressed outward into engagement with said guideways and transversely-operating spring-pressed lateral guiding members in said shoes.

5. In a self-aligning curtain-fixture, a curtain, shoes mounted on said curtain to reciprocate with respect thereto and to coöperate with guideways, separated face guiding members in said shoes, means to yieldingly press said shoes outward, lateral guiding members in said shoes and means to yieldingly force said lateral guiding members, transversely into engagement with said guideways.

6. In a self-aligning curtain-fixture, a curtain, shoes mounted on said curtain to reciprocate with respect thereto and to coöperate with guideways, rotary separated face guiding members in said shoes, means to yieldingly press said shoes outward and transversely operating lateral guiding members in said shoes.

7. In a self-aligning curtain-fixture, a shoe to coöperate with a guideway, said shoe comprising separated guiding members, means to

yieldably force said guiding members into engagement with said guideway, lateral guiding members, including a movable grip, means to force said movable grip transversely into 15 lateral engagement with said guideway and manual means to retract said movable grip.
